Primary Examiner — Phillip S Hyder

(74) Attorney, Agent, or Firm — Ohlandt, Greeley,
Ruggiero & Perle, LLP(57) **CLAIM**

The ornamental design for a tool handle, as shown and described.

DESCRIPTION

FIG. 1 is a front perspective view of a tool handle according to the present disclosure;

FIG. 2 is a rear view of the tool handle of FIG. 1;

FIG. 3 is a first side view of the tool handle of FIG. 1;

FIG. 4 is a front view of the tool handle of FIG. 1;

FIG. 5 is a second, opposite view of the tool handle of FIG. 1;

FIG. 6 is a top view of the tool handle of FIG. 1; and,

FIG. 7 is a bottom view of the tool handle of FIG. 1.

The broken lines in the drawings form no part of the claimed design.

1 Claim, 6 Drawing Sheets(56)
